UNITED STATES PATENT OFFICE.

FREDERICK P. ROSBACK, OF CHICAGO, ILLINOIS.

STAPLE FORMING AND DRIVING MACHINE.

SPECIFICATION forming part of Letters Patent No. 630,303, dated August 1, 1899.

Application filed March 17, 1899. Serial No. 709,532. (No model.)

To all whom it may concern:

Be it known that I, FREDERICK P. ROSBACK, a citizen of the United States, residing at Chicago, in the county of Cook and State 5 of Illinois, have invented a new and useful Improvement in Staple Forming and Driving Devices, of which the following is a specification.

My invention relates to improvements in 10 devices for forming and driving staples, and more especially, though not necessarily, to devices of this class employed as parts of or attachments for machines for making box-blanks.

15 To clearly illustrate my present invention, it is shown in connection with a box-blank-making machine also of my invention and substantially of the construction illustrated in Letters Patent No. 614,348, dated November 15, 1898, and although certain of the details shown are provided to adapt my improvements to the said machine my invention in its broad sense is not to be limited to its connection with a box-blank-making machine, as it may be employed alone or in various other connections for making staples or for forming and driving them.

20 My object is to provide a device of simple and durable construction which will make 30 and drive a staple in each operation without danger of a miss.

25 In the drawings, Figure 1 is an end elevation of a machine for making box-blanks, showing for clearness of illustration only one of my improved staple forming and driving devices in place; Fig. 2, a plan section taken on line 2 2 of Fig. 1 and showing three of my improved staple forming and driving devices; Fig. 3, an enlarged and broken vertical section taken on line 3 3 of Fig. 1 and 35 viewed in the direction of the arrow; Fig. 3^a, a plan view of a clenching-head forming one of the details in Fig. 3; Fig. 4, an enlarged and broken perspective view showing the 40 staple forming and driving device, its support, and the cross-heads for actuating it; Fig. 5, a broken plan section taken on line 5 5 of Fig. 4; Fig. 6, a view illustrating the first step in the operation of the device; Fig. 50 6^a, a detail showing the wire-straightening block; Fig. 7, an enlarged broken section taken on line 7 7 of Fig. 6; Fig. 8, a view

illustrating the second step in the operation of the device; Fig. 9, a broken and enlarged section taken on line 9 9 of Fig. 8; Fig. 10, 55 a view illustrating the third step in the operation of the device; Fig. 11, an enlarged section taken on line 11 11 of Fig. 10; Fig. 12, a view illustrating the fourth step in the operation of the device; Fig. 13, a detail section showing the same step as Fig. 12, with parts enlarged; Fig. 14, a view of the same character as Fig. 13 and illustrating the final step in the operation of the device; Fig. 15, 60 a perspective view of a sliding wire-end guide 65 and cutter, and Fig. 16 the cutting member of the sliding wire-end guide.

A is a box-blank-making machine, and B my improved staple forming and driving devices.

70 C is the drive-shaft of the machine, D a swinging frame suspended from the shaft C and having two cross-bars D' D², and D³ D⁴ cross-heads actuated from eccentrics on the shaft C to reciprocate vertically in the 75 frame D.

Each staple forming and driving device B is formed with a block or back plate t, from 80 which extends a rigid arm s and a removable face-plate r. On the rear side of the block t are upper and lower backward-extending lugs t' t², respectively, which fit over the bar D'. In the said bar is a longitudinally-extending T-groove q, and in the back plate is a bolt-opening for a bolt q', having a T-head to fit 85 the groove q, whereby the device is fastened in proper position upon the bar D' and secured rigidly in place.

E is a staple-forming bar working in a vertical groove or recess ¹³ in the block t. In the 90 rear side of the bar E is a longitudinally-extending T-groove p, and in the said groove is a staple discharging or driving bar F. The forming-bar E is provided at its upper end with a backward-extending shoulder E', extending into a recess n in the cross-head D³, and the driving-bar F is provided at its upper end with a backward-extending shoulder F', which extends into a recess n' in the cross-head D⁴.

95 G is a yielding anvil, consisting of a stem m, a cylindrical body portion m', and upper and lower jaws m² m³, with a horizontal space or recess m⁴ between them. The anvil ex-

tends through a socket t^4 in the block t and is pressed normally forward by a spring m^5 to extend at its jaws into the vertical groove t^8 . The upper jaw m^2 is cam-shaped, and the lower jaw m^3 , by preference, also. In the forward side face of the arm s , adjacent to the vertical groove t^8 , is a guide-recess s' for a horizontally-sliding wire-end guide and cutter-block H . The cutter-block consists of two relatively-movable members $H' H^2$. Connected with the cutter-block is a bell-crank lever H^3 , the connection being through the medium of a pivotal link H^4 . The bell-crank lever is pivoted to a bracket t^6 on the block t , and integral with the bell-crank lever is an upward-extending arm H^5 .

H^6 is a cutter-operating bar at the side of the forming-bar E and provided at its upper end with a backward-extending shoulder H^7 , extending over the top of the cross-head D^4 . On the shoulder H^7 is a set-screw H^8 in the path of the upper surface of the cross-head D^4 . A spring H^9 , connected at opposite ends respectively with the block t and bar H^6 , tends normally to draw the said bar in the downward direction. The lower end portion of the bar H^6 is provided with a lip H^{10} , (see Fig. 11,) which extends under a shoulder H^{11} of the block H^2 , the connection between the two being such that the cutter-block may slide horizontally without releasing engagement with the lip H^{10} . In the face of the block or member H^2 is a horizontally-extending and gradually-reducing groove H^{12} , terminating in an opening and shearing edge H^{13} , and securely fastened to the member H' is a cutter-plate H^{14} , overlapping the member H^2 and having a recessed cutting edge H^{15} . When the member H^2 is in its normal relation to the member H' , there is an opening between the cutting edges $H^{13} H^{15}$ for the passage of a staple-wire Y .

On the arm s are a stationary wire-guide l and a pivotal spring-pawl l' .

K is a wire-feeding block which slides upon the arm s . The block K carries a wire-guide K' and a spring-pawl K^2 .

L is a movable bar mounted toward opposite ends on links $L' L^2$, respectively, which are pivoted to a bar A , forming part of the main frame of the machine. The link L^2 is one arm of a bell-crank lever, the other arm L^3 of which is provided with a longitudinally-extending slot i . (See Fig. 2.) The bell-crank lever is connected by means of a rod i' with an eccentric i^2 on one of the shafts of the machine, whereby in the turning of the shaft the bar L is reciprocated laterally in the horizontal plane. The distance of movement of the bar L may be varied by the adjustment of the rod i' in the slot i , as will be readily understood. On the sliding block K is a post K^3 , carrying a head K^4 .

M is a connecting-rod provided at one end with a head M' , which pivotally engages the post K^3 , and at its opposite end with a slotted head or yoke M^2 , which receives a screw-stud

L^4 on the bar L . In the end of the yoke is a tightening-screw M^3 to engage the stud L^4 . Adjustably fastened in the head K^4 is a finger K^5 to engage the bell-crank lever H^3 , and extending through and adjustable in the head K^4 is a set-screw K^6 to engage the arm H^5 , all as hereinafter described.

On the end of the arm s is a projecting lug f , carrying a vertical set-screw f' , and pivoted upon the said end at f^2 is a swinging wire-straightening block f^3 just in advance of the wire-guide l . The block f^3 is adjusted by means of the set-screw f' .

Initially the parts are in the position shown in Figs. 3, 4, and 6, and the wire Y is placed in position by passing it through an eye d on the bar L , thence under the straightening-block f^3 , through the guide l under the pawl l' , thence through the guide K under the pawl K^2 , and thence through the gradually-reducing groove H^{12} in the cutter-block member H^2 . The opening at $H^{13} H^{15}$ is close to and in line with the space m^4 between the jaws $m^2 m^3$ of the anvil G . In the rotation of the shafts of the box-blank-making machine the bar L and connecting-rod M are moved in the direction toward the right in Fig. 3 to feed the staple-wire across the anvil G and causing the finger K^5 to slide from the top of the bell-crank lever H^3 and also causing the set-screw K^6 to engage the arm H^5 and move the cutter-block H to the left away from the anvil G , all as shown in Fig. 8. As soon as the cutter-block arrives at this position the cross-head D^4 engages the set-screw H^8 on the cutter-operating bar and by lifting the latter draws the sliding member H^2 of the cutter-block in the upward direction, causing the wire to be sheared off by the cutting edges $H^{13} H^{15}$. At this point the cross-head D^4 reaches the limit of its rise, while the cross-head D^3 is descending. The cross-head D^3 at the upper side of its groove n engages the shoulder E' of the forming-bar E and presses the latter downward past the jaws of the anvil. The T -groove p of the forming-bar causes the latter to clear the anvil, while the lower end of the bar moves from the position shown in Figs. 8, 9, and 10 to engage the staple-wire at opposite sides of the anvil and form the staple Y' , as shown, for example, in Fig. 13. As will be seen in that figure, the staple is formed over the jaw m^3 of the anvil, the legs of the staple being in the lateral slots of the T -groove p of the forming-bar. While a staple is being formed as described the cross-head D^4 commences its downward movement. The block K continues its movement toward the right to feed the staple-wire toward the anvil, and the cross-head D^4 presses down the driving-bar F . The lower end of the driving-bar F engages the cam-surface of the jaw m^2 of the anvil and presses the latter out of its path against the resistance of the spring m^5 and engages the top of the staple and drives it downward out of the forming-bar, as illustrated in Fig. 14. The cross-head D^3 rises while

the block K continues its movement toward the right to feed the staple-wire toward the anvil, and the cross-head D^4 presses down the driving-bar F . The lower end of the driving-bar F engages the cam-surface of the jaw m^2 of the anvil and presses the latter out of its path against the resistance of the spring m^5 and engages the top of the staple and drives it downward out of the forming-bar, as illustrated in Fig. 14. The cross-head D^3 rises while

the staple is being discharged, and at the completion of the discharge the lower edge of its groove n engages the shoulder on the forming-bar E and raises the latter upward past the anvil. The cross-head D^4 also commences to rise at about the same time that the forming-bar commences its upward movement, so that both the driving-bar and forming-bar are raised above the anvil and the latter is released and springs forward just before the end of the wire for the next staple reaches the recess t^3 of the block t . The engagement of the finger K^5 with the arm of the bell-crank lever H^3 moves the block H very quickly along the staple-wire to the end portion of the latter and close to the anvil, whereby the cutter-block operates to guide the end of the wire through the anvil-opening m^4 . The cutter-block remains in this position until in the final movement of the block K the screw K^6 contacts with the arm H^5 and moves the cutter-block quickly along the wire to its cutting position, at which position it remains momentarily stationary during the change in direction of movement of the bar L and attendant parts, and at this moment the cross-head D^4 reaches the limit of its rise to raise the cutter-bar and starts to descend to release the cutter-bar. In the backward movement of the block K the wire is held against retraction by the pawl l' , the pawl K^2 sliding freely over the wire, while in the movement of the block K in the direction to the right the pawl K^2 grips the wire to feed it, the wire moving readily under the pawl l' . The length of one staple-leg may be changed by changing the adjustment of the connecting-rod i' in the slot i to increase or diminish the throw of the bar L , and the position of the cutter-block H at the time the cutting of the wire is effected may be changed by adjusting the set-screw K^6 . Thus the end of the set-screw may be caused to engage the arm H^5 and move the cutter-block to a position where the length of the staple-legs will be the same when the cutting is effected.

In the operation of the box-blank-making machine a blank Z and strengthening-wires Z' are fed across the lower ends of the staple forming and driving devices, the staples being driven into the blank to straddle the strengthening-wires and preferably clenched. Adjustably fastened upon the bar D^2 beneath each staple forming and driving device is a block N , to which is secured a post N' , provided at its top with a clencher-plate N^2 of the form shown in Figs. 3 and 3^a. The post N' may be raised and lowered to position it upon the block N by means of an adjusting-screw N^3 . As the staples are driven their ends strike grooves c in the clencher-plate and are upset to clinch the staples. Fastened against the face-plate r is a bar b , provided at its lower end with a presser-roller b' , and on the upper end of the bar N' is a presser-roller N^4 . After a staple has been driven and the blank material is fed along the staple passes be-

tween the rollers $b' N^4$ and the clenched ends are pressed into the under surface of the blank.

My improved staple forming and driving device, while particularly desirable for use in connection with a box-blank-making machine such as described, is a complete device in itself and may be employed alone or in any other connection where operating mechanism is suitably adapted.

In the construction described the cutter-block H , it will be understood, performs two functions—namely, those of a wire-end guide for directing the wire to the anvil and of a wire-cutter. It moves to its wire-end-guiding position to insure the proper positioning of the wire at the anvil and then moves out of the way, so as not to obstruct the wire in the bending operation. While the wire-end guide and cutter in the present construction are one piece of mechanism, I do not wish to be limited thereto, as I believe it to be novel to provide a movable wire-end guide operating as set forth.

While I prefer to construct my improvements as shown and described, they may be variously modified in the matter of details of construction without departing from the spirit of my invention as defined by the claims.

What I claim as new, and desire to secure by Letters Patent, is—

1. In a staple-forming device, the combination with the staple-forming anvil and the wire feeder, cutter, staple forming and discharging mechanisms and their actuating means, of a wire-end guide movable to one position to guide the wire to the anvil and movable from said position to be out of the way in the staple-bending operation, substantially as described.

2. In a staple-forming device, the combination with the staple-forming anvil and the wire-feeder, staple forming and discharging mechanisms and their actuating means, of a sliding wire-end guide and cutter movable toward the anvil to guide the wire, and movable away from the anvil to its cutting position, and means for operating the cutter, substantially as described.

3. In a staple-forming device, the combination with the staple-forming anvil, cutter, staple forming and discharging mechanisms and their actuating means, of a reciprocating wire-feeder and a wire-end guide actuated by movement of the wire-feeder to move to one position to guide the wire to the anvil and to move from said position to be out of the way in the staple-bending operation, substantially as described.

4. In a staple-forming device, the combination with the staple-forming anvil, staple forming and discharging mechanisms and their actuating means, of a reciprocating wire-feeder, a wire-end guide and cutter actuated by movement of the wire-feeder to move toward the anvil to guide the wire and to move away from the anvil to its cutting position,

- and means for operating the cutter, substantially as described.
5. In a staple-forming device, the combination with the staple-forming anvil and the staple forming and discharging mechanisms and their actuating means, of a reciprocating wire-feeder, a sliding wire-end guide and cutter between the wire-feeder and anvil actuated by movement of the wire-feeder to move toward the anvil to guide the wire and to move away from the anvil to its cutting position, and means for operating the cutter, substantially as described.
6. In a staple-forming device, the combination with the staple-forming anvil and the staple forming and discharging mechanisms and their actuating means, of a reciprocating wire-feeder, a sliding wire-end guide and cutter between the wire-feeder and anvil, an operating-lever for said guide and cutter in the path of the said wire-feeder and actuated thereby to move toward the anvil to guide the wire and then move away from the anvil to its cutting position, and means for operating the cutter, substantially as described.
7. The combination with the cross-heads and their operating means, of a staple-forming and driving device having a staple-forming anvil, staple forming and driving mechanisms operatively connected with said cross-heads, a reciprocating wire-feeder, a sliding wire-end guide and cutter thereon operatively connected with one said cross-head, the wire-end guide being actuated by the wire-feeder to move toward the anvil to guide the wire and to then move away from the anvil to the cutting position, substantially as described.
8. The combination with the main frame and drive-shaft, of the operating-bar L operatively geared to the drive-shaft to be oscillated thereby, and a plurality of staple forming and driving devices provided with wire-feeders connected with said bar to be actuated thereby in unison, substantially as described.
9. The combination with the main frame and drive-shaft, of the operating-bar L operatively geared to the drive-shaft to be oscillated thereby and adjustable to vary its throw, and a plurality of staple forming and driving devices provided with wire-feeders connected with said bar to be actuated thereby in unison, substantially as described.

FREDERICK P. ROSBACK.
